(57) **CLAIM**

The ornamental design for a blood glucose cartridge, as shown and described.

DESCRIPTION

FIG. 1 is a perspective view of a blood glucose cartridge showing our new design;

FIG. 2 is another perspective view thereof;

FIG. 3 is a top view thereof;

FIG. 4 is a front view thereof;

FIG. 5 is a right side view thereof;

FIG. 6 is a left side view thereof;

FIG. 7 is a bottom view thereof; and,

FIG. 8 is a rear view thereof.

The broken lines showing the glucose meter in FIGS. 1 and 2 illustrate environmental structure. Other broken lines illustrate unclaimed portions of the blood glucose cartridge. None of the broken lines form a part of the claimed design.
